UNITED STATES PATENT OFFICE

167,508

COAT

Joseph Feldman, New York, N. Y.

Application April 11, 1952, Serial No. 19,290

Term of patent 7 years

(Cl. D3—4)

To all whom it may concern:

Be it known that I, Joseph Feldman, a citizen of the United States of America, residing in New York city, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

Fig. 3 is a front view of the coat as shown in Fig. 1 with the panel portion folded down into a muff arrangement. The characteristic feature of my design resides in the muff arrangement on the waist portion of the coat as shown.

I claim:

The ornamental design for a coat, substantially as shown and described.

JOSEPH FELDMAN.
